UNITED STATES PATENT OFFICE.

NELSON F. HOWARD, OF FAIRFIELD TOWNSHIP, TIPPECANOE COUNTY, INDIANA.

FENCE-TIGHTENING POST.

1,183,562.

Specification of Letters Patent.

Patented May 16, 1916.

Application filed October 12, 1912. Serial No. 725,395.

To all whom it may concern:

Be it known that I, NELSON F. HOWARD, a citizen of the United States, residing in Fairfield township, in the county of Tippecanoe and State of Indiana, have invented a new and useful Fence-Tightening Post, of which the following is a specification, reference being had to the accompanying drawings and to the letters and figures of 10 reference marked thereon.

This invention relates to posts that are designed to tighten and support wire fencing and also metallic rails and which are suitable for gate posts; the invention having reference more particularly to a composite post of such construction as to be especially adapted for end or corner posts for either farms or town lots.

An object of the invention is to provide 20 a thoroughly reliable, strong and durable fence post that shall be so constructed as to be capable of withstanding strains due to tightly stretched wire fencing and not be so large as to be cumbersome or unsightly.

25 A further object is to provide a fence tightening post of such construction that when located as an end post at a desired gateway the gate may be hung on the post.

30 A still further object is to provide a fence tightening post that may be set either in a concrete base or in the ground, as may be desired.

With the above mentioned and other objects in view which may hereinafter appear, the invention consists in a post comprising various novel features of construction, the invention consisting also in the novel parts and in the combinations and arrangements of parts as hereinafter particularly described and further defined in the 40 accompanying claims.

Referring to the drawings, Figure 1 is an elevation of a section of fencing partially broken away, constructed substantially in 45 accordance with the invention; Fig. 2, a fragmentary sectional plan on the plane of the line A A in Fig. 1; Fig. 3, a top plan of the post with the upper portion omitted; Fig. 4, an inverted plan of the upper portion of the post; Fig. 5, a vertical central sectional view of the post; Fig. 6, a fragmentary elevation of the stem of the post; Fig. 7, an elevation of the rotatable portion 50 of the post or the reel whereby the fencing wires are tightened and directly supported; Fig. 8, an elevation partially in section of

the reel partially turned relative to the preceding figure; Fig. 9, a horizontal section on the plane of the line B B in Fig. 1; Fig. 10, a fragmentary section on the line C C 60 in Fig. 7; Fig. 11, a perspective view of a suitable device for connecting the fence wires to the reel or winding portion of the post; Fig. 12, a fragmentary section of the complete post on the line C C; and Fig. 13, a vertical section of the upper or cap portion of the post.

Similar reference characters in the different figures of the drawings indicate like parts or features of construction herein referred to.

As preferably constructed, a metallic tube 1 is employed which preferably has a tapering flattened end portion 2 to prevent the tube from rotating when properly set 75 uprightly, the tube comprising the stem which supports the remaining portions of the post and which preferably has a concrete core 3. The upper portion of the stem has a vertical slot 4 therein extending 80 downward from the top of the stem as a means for preventing slackening of the wire fencing. A tubular winding portion 5 is provided which is of suitable diameter to rotate on the stem, and it is somewhat 85 shorter than the stem, the normal upper end of the winding portion or reel having ratchet teeth 6 thereon. Preferably the stem 1 has a collar 7 on its lower portion and secured thereto by a set screw 8, the 90 position of the collar being approximately at the ground line so as to support the winding portion 5 with the upper end at a suitable height somewhat below the plane of the top of the stem. The winding portion 5 95 has a suitable number of horizontally arranged tangential apertures 9 in the wall thereof of which may be either drilled or cored in the wall to receive fencing wires. A cap or head 10 is provided of suitable form to 100 cover the stem and the winding portion, and it has a cylindrical portion 11 that is rotatably guided on the upper portion of the stem and provided on its lower end with ratchet teeth 12 that ride upon the ratchet 105 teeth 6 when rotated in one direction and engage the teeth 6 to prevent relative movement in the opposite direction, a hood 13 preferably being formed so as to extend about the upper portion of the reel and 110 cover all the ratchet teeth, and the interior of the cap is provided with a cross-bar 14

that is cast integral with the cylindrical portion 11 and extends movably into the slot 4 and prevents the cap or head from rotating on the stem but may move vertically, the movement of the teeth 6 against the teeth 12 forcing the cap upward to fall again by force of gravity and prevent reverse movement of the reel.

The post is provided with a concrete base 10 in which the lower portion of the stem is embedded either before or after the post is placed in position in the ground, and when provided with a base the winding portion 5 may rest upon the base so that the collar 15 7 may be dispensed with.

When it is desired to place spreaders between posts to resist strains due to tight fencing wires or to provide a fence with metallic rails above the wire fencing, a collar 20 16 is secured by a set screw 17 on the winding portion 5, and a suitable pipe fitting similar to a T is employed the larger cylindrical main portion 18 of which is placed rotatably on the winding portion 5 and is supported on the collar 16, the lateral branch portion 19 of the fitting extending toward the next adjacent post, so that two adjacent posts have main portions 18 and 18'. The side portions 19 and 19' of the fittings extend each toward the other and have a hollow rail 20 formed of tubing secured thereto, the rail being arranged at a suitable height, preferably near the tops of the posts, and it is obvious that additional rails may be similarly connected to the posts.

When it is desired to hang a gate to one of the improved posts a collar 21 is secured by a set screw 22 on the lower portion of the reel. A suitable gate 23 having hinge members 24 and 25 is suitably arranged and the hinge members preferably extend about the winding portion 5 so that the gate may swing on the post and permit the winding portion to rotate when the gate is at rest, the lower hinge member 24 being supported upon the collar 21. The gate may be latched to a suitable gate post 26 arranged at the opposite end of the gate.

Fencing wires 27, either strung singly or 50 as portions of woven wire fencing, are inserted through the apertures 9 or otherwise secured to the reel and are then stretched, and in some cases a wire 28 is similarly connected to two posts above the rail 20, the ends 29 of the wires being looped to prevent slipping of the wires. In some cases a plate 30 is employed which has a hook 31 that is inserted in an aperture 9, and the plate has a suitable number of studs 32 on its outer 55 side between which a fence wire is drawn so as to become crimped and held by the studs so that the wire becomes stretched when the reel is rotated, the wires being further secured to the post if desired.

60 In practical use, the posts stand firmly and

when the rails 20 are not designed as parts of the fencing it may be found advantageous to employ them between the end or corner posts and the next adjacent post so that the latter assists in bracing the end or corner 70 post. In case the wire fencing becomes slightly slack it may readily be tightened by placing powerful pipe tongs on the winding portion 5 and rotating it until the wires are taut, the winding portion or reel being 75 automatically locked by the cap when released.

Having thus described the invention, what is claimed as new is:—

1. A fence post including a cylindrical 80 stem having a slot in its upper end, a tubular winding portion rotatable on the stem and having ratchet teeth on its upper end, and a cap movably guided on the upper end of the stem and having a cross-bar therein 85 extending into the slot, the cap having also ratchet teeth on its lower end engaging the teeth of the winding portion.

2. A fence post including a cylindrical 90 stem, a tubular winding portion rotatable on the stem and having apertures in the wall thereof, plates having studs thereon and having also each a hook inserted in an aperture, and a cap on the top of the stem automatically locking the winding portion 95 against rotation in one direction and permitting rotation in the opposite direction.

3. A fence post including a cylindrical 100 stem, a tubular winding portion rotatable on the stem and having ratchet teeth on the upper end thereof and having also apertures extending transversely into and out of the exterior of the wall thereof, a cap movable vertically on the upper end of the stem and having ratchet teeth on its lower end engaging the teeth of the winding portion, the cap having also a hood thereon extending over and about all the teeth and means for preventing rotation of the cap on the stem. 105

4. A fence post including a hollow cylindrical stem having a solid core secured therein, the upper end of the stem having a vertical slot therein, a cap movable vertically on the stem and having a cross-bar therein extending into the slot, the lower end of the cap having a hood and also ratchet teeth in the hood, and a winding portion rotatable on the stem and extending into the hood, the upper end of the winding portion having ratchet teeth thereon engaging the teeth of 120 the cap. 115

5. A fence post including a base, a cylindrical stem having a flattened lower end portion embedded in the base, a tubular winding portion rotatable on the stem and extending from the base toward but not entirely to the upper end of the stem, the upper end of the winding portion having ratchet teeth thereon, and a cap movable vertically on the upper end of the stem and 125 130

locked against rotation thereon, the lower end of the cap having ratchet teeth engaging the teeth of the winding portion.

6. A fence post including a hollow cylindrical stem having a flattened lower end portion, the upper end of the stem having a vertical slot therein, a collar secured to the stem, a tubular winding portion rotatable on the stem and supported on the collar, the upper end of the winding portion having ratchet teeth thereon, a cap movably guided on and covering the upper end of the stem and having ratchet teeth on its lower end engaging the teeth of the winding portion, and a cross-bar in the slot of the stem and cooperating therewith and with the cap for preventing rotation but permitting vertical movement of the cap.

7. In a fence-tightening post, the combi-

nation of a cylindrical stem having a flattened lower end portion to prevent rotation thereof, a tubular winding part rotatable on the stem and constructed for winding fencing thereon, means for locking the winding part to the stem against rotation of the part in one direction, a collar fixedly secured to the winding part, a connecting device comprising a hollow main portion loosely embracing the winding part upon said collar and permitting rotation thereof, the device having a hollow lateral branch, and a tubular brace inserted and secured in said branch.

In testimony whereof, I affix my signature in presence of two witnesses.

NELSON F. HOWARD.
